UNITED STATES PATENT OFFICE.

JOHN L. BURNET, OF CARLISLE, ARKANSAS.

SHOE-BROOM.

977,432.

Specification of Letters Patent.

Patented Dec. 6, 1910.

Application filed August 19, 1910. Serial No. 578,011.

To all whom it may concern:

Be it known that I, JOHN L. BURNET, a citizen of the United States, residing at Carlisle, in the county of Lonoke, State of Arkansas, have invented certain new and useful Improvements in Shoe-Brooms; and I do hereby declare the following to be a full, clear, and exact description of the invention, such as will enable others skilled in the art to which it appertains to make and use the same.

This invention relates to shoe polishing machines, and has for its object to provide a device of this character that may be readily attached to a door jamb or porch post and will be composed of a few simple parts that will not easily get out of order and will be so arranged as to permit of a worn-out cleaning brush being replaced with a fresh brush more easily than in devices of this character hitherto.

To attain these ends, the invention consists of the novel details of construction and combination of parts hereinafter fully described and claimed, it being understood that various modifications may be made in the minor details of construction within the scope of the appended claims.

In the accompanying drawings forming part of this specification:—Figure 1 is a side elevation of the device. Fig. 2 is a side elevation of the shoe broom at right angles to that shown in Fig. 1. Fig. 3 is a cross sectional view taken on the line 3—3, Fig. 1. Fig. 4 is a fragmentary sectional view showing the driving shaft upper mounting. Fig. 5 is a fragmentary sectional view showing the driving shaft lower mounting.

Referring now to the drawing, the reference numeral 10 designates in general the support which is designed to be secured by screws or similar connectors to a porch post, door jamb or the like. The support is formed from a single strap of metal having its terminals bent laterally, one of these terminals 11 carrying the driving shaft upper journal box and the other terminal 12 carrying the driving shaft lower journal box, this latter named terminal being arranged parallel with the floor and being provided at its outer end with a downturned foot 13 which is secured to the floor by screws or similar connectors 14.

The driving shaft 15 is mounted in upright position upon the support and is equipped adjacent its lower end with a cir-

cular brush 16, a key 17 removably securing the brush to the shaft. The brush it will be noted lies in a horizontal plane so that an entire side of a shoe or boot may be cleaned when the brush is rotated. For scraping accumulations of dirt from the brush an L shaped scraper 18 is bolted as shown at 19 to the support and bears with its free edge against the periphery of the brush. 65

For actuating the driving shaft the following construction is employed:—A bevel gear 20 is fixed upon the upper end of the driving shaft and meshes with a bevel gear 21 carried upon a reduced circular extension 70 22 formed integral with the uppermost arm 11 of the support. A crank handle 23 is fixed to the bevel gear 22 and forms means for rotating the gears and driving the shaft.

For removably securing the shaft so as 75 to permit of its being raised vertically whereby the brush may be slipped downward and removed from the lower end of the shaft and replaced with a new one, a bearing 24 is provided axially with a square 80 extension 25, this extension fitting in a squared opening 26 formed in the uppermost arm 11 of the support. The driving shaft is journaled in the bearing, the squared neck of the bearing preventing the rotation of the 85 latter during the rotation of the shaft. A collar 27 is secured to the driving shaft by means of a set screw or similar device 28, this collar bearing against the lower face of the uppermost arm 11 and preventing the 90 displacement of the driving shaft. When it is desired to lift the shaft vertically the set screw is loosened and the collar slid downward upon the driving shaft when the driving shaft may be lifted bodily until its 95 lower end clears the lowermost arm 12 of the support, when a new brush may be inserted in position in place of the worn-out brush.

Fitted in an opening 29 formed in the 100 lowermost arm of the support is a journal box 30 having a marginal flange 31 which bears against the top face of the lowermost arm and retains the box in position. The box is provided in its bore with a ball race 105 32 in which balls 33 are fitted and bear against the driving shaft and permit of the latter being freely rotated. Both edges of the lowermost arm are cut away as shown at 34 to form a scraper against which the 110 soles of the shoes may be rubbed to remove accumulations therefrom.

What is claimed is:—

1. A shoe cleaning device having a support formed from a single length of material having a straight portion for securing the device and having outwardly bent arms one of which is adapted to be secured to a floor or similar support, a bevel gear carried by the other of said arms, an upright driving shaft journaled in said arms and having a bevel gear meshing with the first named bevel gear, and a horizontally disposed brush removably mounted upon said driving shaft.
2. A shoe cleaning device having a support formed from a single length of material having a straight upright securing portion, and having laterally bent arms, one of which

is equipped with a downturned foot for securing the device, and further is equipped with a journal box, and the other of said arms having a journal box, a shaft rotatably mounted in said journal boxes, means for actuating the shaft, a collar on the shaft bearing against the lower face of said arm and movable longitudinally on said shaft, to permit of the shaft being raised vertically free from its lower journal box, and a disk brush removably secured to the shaft.

In testimony whereof, I affix my signature, in presence of two witnesses.

JOHN L. BURNEY.
